UNITED STATES PATENT OFFICE.

SIMEON H. LUCAS, OF SAN BERNARDINO, CALIFORNIA.

DESIGN FOR A BROOCH.

SPECIFICATION forming part of Design No. 17,916, dated November 29, 1887.

Application filed September 10, 1887. Serial No. 249,397. Term of patent 7 years.

To all whom it may concern:

Be it known that I, SIMEON H. LUCAS, of San Bernardino, San Bernardino county, State of California, have invented and produced a new and original Design for a Brooch, of which the following is a specification.

My invention relates to jewelry, and comprises a design for a brooch, consisting of the conventional representation of an orange branch, showing the ripe and unripe fruit, with the leaves and blossoms.

Referring to the accompanying drawings for a more complete explanation of my invention, Figure 1 is a view of the brooch. Fig. 2 shows the ear-ring.

A is an orange branch, having the ripe fruit B and the leaves and unripe fruit C and D,

while E represents the blossoms. The ear-rings represent a single orange.

Having thus described my invention, what I claim as new, and desire to secure by Letters Patent, is—

A design for a brooch, consisting of the conventionalized representation of ripe and unripe oranges on the branch, with the leaves and blossoms, substantially as herein shown and described.

In witness whereof I have hereunto set my hand.

SIMEON H. LUCAS.
